UNITED STATES PATENT OFFICE

2,406,151

CAN END MARKING MEANS

Alfred L. Kronquest, Syracuse, N. Y., assignor to
 Continental Can Company, Inc., New York,
 N. Y., a corporation of New York

Original application December 7, 1940, Serial No.
 369,110. Divided and this application November
 24, 1943, Serial No. 511,611

8 Claims. (Cl. 101—6)

1

The invention relates to marking means and primarily seeks to provide a novel and efficiently operable heavy duty marking means capable of embossing suitable identifying markings on can ends or closures as they are being rapidly moved from a supply stack into position for being assembled with cans to be closed in a closing machine.

Marking means employing opposed male and female marking dies engageable with can end closures for applying identifying markings thereon have been provided heretofore, but the use of such means has been attended by disadvantages and problems have been presented by reason of certain limitations upon the speed of use thereof, inability to successfully cope with operation strains incident to heavy duty marking or markings in which more than the customary line or two of embossed letters are included, and lack of proper adjustability of the opposed relation of the marking dies. The present invention seeks to provide a novel marking means which will overcome these disadvantages and limitations, and the present application constitutes a division of my former co-pending application for U. S. Letters Patent, filed December 7, 1940, Serial No. 369,110, which eventuated into Patent 2,362,206 on November 7, 1944.

An object of the invention is to provide a novel marking means of the character stated in which the male and female die elements oppose by a movement of rotation, and in which novel means is provided for adjusting the spaced relation of the die elements so as to regulate the pressure of said elements against the metal of the end closures being marked.

Another object of the invention is to provide a novel marking means of the character stated in which the adjustment of the spacing of the die elements is effected by movement of an eccentric sleeve about the axis of one of the rotary elements, and in which means is provided for justifying slight misalignments of the male and female die elements occasioned by adjustments of said sleeve.

With the above and other objects in view which will hereinafter appear, the nature of the invention will be more fully understood by following the description, the appended claims and the several views illustrated in the accompanying drawings.

In the drawings:

Figure 1 is a front elevation of the marking means and a part of the closing machine on which said means is adjustably mounted.

2

Figure 2 is a vertical cross-sectional view of the marking means taken substantially on the line 2—2 on Figure 1.

Figure 3 is a horizontal sectional view taken substantially on the line 3—3 on Figure 2.

Figure 4 is an enlarged end elevation illustrating the opposed marking elements and their carrying shafts.

Figure 5 is an enlarged fragmentary vertical cross-sectional view through the adjustable mounting of the upper marking element.

The improved container end closure marking mechanism is herein illustrated as vertically-adjustably mounted on a container closing machine which may be of any suitable form including a frame structure generally designated 5 on which is mounted a six station closing turret 6 to which filled containers 7 and end closures 8 therefor are fed by a pocketed feed turret 9. The feed turret 9 includes seats 10 for receiving and positioning the end closures 8 in proper relation above the containers 7 which are fed one by one into the pockets of the turret 9 by any suitable container feed-in means generally designated 11. The end closures are suitably marked while they are being moved from a supply stack toward the receiving seats 10 of the turret 9, and it is the purpose of the present invention to provide a novel marking mechanism particularly adapted to heavy duty marking of the end closures with all over markings as distinguished from the usual one or two line marking customarily applied.

The frame 5 includes a mounting pad 12 and a marking means mounting bracket extension 13. The frame also includes a casing and bearing extension 14 equipped with a vertical shaft bearing 15, a vertical shaft bearing 16, a vertical shaft bearing 17, and a horizontal shaft bearing 18.

A sleeve 19 is rotatably mounted in the bearing 15 and carries a gear 20 which meshes with and is driven by a gear 21 to which rotation is imparted from a moving part of the closing machine. A spline shaft 22 passes vertically through the sleeve 19 thereby being connected for rotation with the sleeve and the gear 20 and also mounted for vertical adjustment relative to said sleeve and gear.

The gear 20 imparts rotation to one of a pair of co-axially mounted idler gears 23 and the other of said idler gears meshes with and imparts rotation to a gear 24 fixed to a sleeve 25 which is rotatably mounted in the vertical bearing 16. A spline shaft 26 is rotatable with and

vertically slideable through the sleeve 25 and gear 24, and the purpose of this shaft 26 and the spline shaft 22 and the vertically adjustable nature thereof will later be described.

A sleeve 27 is rotatably mounted in the vertical bearing 17 and has a screw column 28 threadably mounted therein in the manner best illustrated in Figure 2 of the drawings. A bevel gear 29 is fixed to the lower end of the sleeve 27 and meshes with a bevel gear 30 fixed on a shaft rotatable in the horizontal bearing 18 and which is equipped at its outer end with a hand wheel 31. It will be obvious by reference to Figure 2 of the drawings that by rotating the hand wheel 31, vertical movement can be imparted to the screw column 28 upwardly or downwardly through the captive sleeve 27 according to the direction of rotation imparted to said hand wheel.

A bracket plate 32 is vertically-adjustably secured to the mounting pad 12 by slot and screw equipments 33, and this bracket plate includes a flange portion 34 to which is affixed a supporting table or plate 35 which overlies the feed-in turret 9 of the closing machine and is equipped with end closure guideways 36 over which end closures are conveyed from a supply, through the marking station and onto the receiving seats 10 of the turret 9. The marked end closures are delivered onto the receiving seats as at 37. See Figure 3.

The table or supporting plate 35 carries an end closure supply stack or feeding means generally designated 38. This end closure feeding means may be of any approved form capable of discharging end closures one by one onto the receiving guideways 36 beneath the supply or stack. See Figures 1 and 3 of the drawings.

The table or plate 35 also supports a depending housing 39 which is equipped with a bearing 40 vertically aligned with the bearing 15 and which has a sleeve 41 secured therein in the manner best illustrated in Figure 2 of the drawings. The sleeve 41 is of a length for extending vertically above the bearing 40 and has its upper end provided with a rim gear portion 42, the purpose of which will later become apparent.

The spline shaft 22 extends upwardly through the bearing 40 and sleeve 41 and has keyed thereon a rotor 43 supported on anti-friction bearings 44 surmounting the sleeve 41. Four shafts 45 are rotatably mounted in equidistantly spaced relation in the rotor 43 and each of these shafts carries a gear 46 at its lower end enmeshed with the rim gear portion 42 of the sleeve 41. It will be obvious that as the rotor 43 rotates about the stationary sleeve 41 the rim gear portion 42 of the sleeve will impart rotation to the gears 46 and the shafts 45 on which they are mounted. At its upper end each shaft 45 carries a head 47 equipped with an off-center crank roller 48, and each roller engages in a radial recess 49 in the under surface of an end closure feeding finger 50 pivotally mounted, as at 51, inwardly of the axis of the associated shaft 45 in the manner best illustrated in Figures 2 and 3 of the drawings. Each of the feeder members 50 is equipped with a feeding finger extension 52 which projects in a generally radial direction to a point centrally disposed between the spaced guides 36 upon which end closures are supported while being moved along by said finger extensions. The marking station through which the end closures are moved by said finger extensions is generally designated 53 in Figure 3 of the drawings.

The rotary closure feeding devices described hereinabove and including the feeding finger extensions 52 which sweep relatively rapidly past the closure supply station and relatively slowly while passing the place at which the marked closures are deposited on the traveling receiving and supporting means are covered in the parent application hereinbefore referred to and no claims are directed to these devices in this application.

10 The adjustable marking devices which form the subject matter of this divisional case will now be described.

The bracket plate 32 carries a bracket extension 54 which is equipped with a mounting pad portion 55 against which a bracket hanger 56 is vertically-adjustably secured through the medium of longitudinal slot and screw equipments 57. The extension 54 also includes an overhanging lug 58 and an adjusting screw 59 threaded through the lug in position for engaging the bracket hanger 56 for imparting movements of adjustments thereto relative to the bracket plate 32 and its extension 54, 55.

A marker body 60 is secured as at 61 to depend from the hanger bracket 56 and has mounting pad portions 62 which are vertically-adjustably secured to the bracket extension 13 through the medium of longitudinal slot and screw equipments 63.

The supporting body 60 of the marking mechanism carries a depending extension 64 having a horizontal bearing 65 formed therein for a rotary shaft 66 which carries a spur gear 67 at one end and a bevel gear 68 at its other end.

The bevel gear 68 meshes with and is driven by a bevel gear 69 secured upon the upper end of the vertically-adjustable spline shaft 26.

The spur gear 67 meshes with a spur gear 70 secured upon the lower marker shaft 71 rotatably mounted in the bearing 72 provided therefor in the marker body 60, and the gear 70 in turn meshes with and drives a spur gear 73 which loosely surrounds a sleeve 74 keyed upon the upper marker shaft 75.

The upper marker shaft 75 is rotatable in an eccentric sleeve bearing 76 which is rotatably supported in the marker body 60 in the manner best illustrated in Figures 2 and 5 of the drawings.

The sleeve 74 carries a lug extension 77 having a longitudinal recess 78 therein for receiving the projected end of a pin 79 carried by the spur gear 73. The portion of the pin 79 which projects into the longitudinal recess 78 is engaged at opposite sides by justifying screws 80. See Figures 2 and 5. It will also be noted by reference to these figures that the sleeve 76 is provided with a worm gear surface 81 which is engaged by an adjusting screw 82 having a turning head 83. By rotating the screw 82 in one direction or the other the eccentric bearing sleeve 76 can be rotated in one direction or the other for altering the position of the axis of rotation of the upper marker shaft 75. By this means the spaced relation of the marker shafts 71 and 75 can be varied for the purpose of adjusting to a nicety the cooperative relation of the marking elements or dies carried by said shafts.

Each of the marker shafts 71 and 75 includes a reduced end 84 extending beyond the marker body 60 and having a seating face 85 against which a die block 86 is secured. The die blocks 86 carry the usual male and female die elements 87 and are removably clamped in position on the shaft extensions by having their stems 88 passed through transverse bores 89 in the shaft exten-

sions and secured therein by screw equipments 90. While the die blocks are shown as equipped with the usual simple form of co-acting male and female elements in Figures 2 and 4 of the drawings, it is to be understood that the present marker is particularly adaptable to use in heavy duty marking wherein the marking dies are equipped to mark the end closures over the whole or a major portion of the surfaces thereof, including curved line embossing which demands precise interengagement of the male and female embossing elements. The opposed male and female die elements engage in rolling contact during actual marking of the end closures and this engagement is effected through a suitable opening 91 provided in the plate or table 35 in the manner best illustrated in Figure 2 of the drawings.

The intermeshing gears 67, 70 and 73 are preferably protected by a removable cover 92 attached to the marker body 60 and its depending extension 64 in the manner clearly illustrated in Figures 1 and 2 of the drawings.

It will be observed that the upper end of the screw column 28 is secured as at 93 to the marker body 60, 64. Thus by loosening the clamping or securing screws 33 and 63 and by rotating the hand wheel 31, upward or downward movement can be imparted to the screw column 28, the marker body 60, 64, the hanger bracket 56, the bracket extension 54, the bracket plate 32, the plate or table 35, and the end closure stack or feed 38 and the depending housing 39 supported by said plate. It will be obvious that spline shafts 22 and 26 will move vertically with the parts just mentioned without disrupting the power transmitting connections to the marking parts or to the end closure feeding devices.

In operation, as the end closures are discharged one by one from the cover feeding means 38 onto the receiving trackways 36 they are engaged by the feeding finger extensions 52 and moved along said guideways. The compound movement imparted to the finger extensions 52 by simple rotation of the rotor 43 and the relative rotation of the heads 47 and the rollers 48 cause the fingers to have one rapid sweep movement and one retarded movement during each rotation of the rotor 43. It will be observed by reference to Figure 3 of the drawings that the marking station 53 is so related to the position 37 at which the marked end closures are deposited on the turret seats 10 that each finger 52 moves an end closure through the marking station during a part of its rapid sweep movement, and moves the marked end closure into position at 37 for being received on the respective turret seat 10 during a part of its retarded or slow sweep movement. While each end closure is being moved past the marking station 53 it is engaged in rolling contact by the opposed male and female die elements 87 and suitably embossed.

When it is desired to adjust the spaced relation of the shafts and the marking dies carried thereby, this can be accomplished with great facility by turning the eccentric sleeve 76. Whenever the screw and eccentric sleeve equipments 82, 76 are adjusted to vary the spaced relation of the shafts 71 and 75, and therefore the cooperative relation of the marking dies, movement of the eccentric sleeve 76 about its axis serves not only to lift or lower the axis of the shaft 75, but also to move the axis of that shaft laterally. This lateral movement of the shaft

75 would upset the perfect registering relation of the male and female embossing die elements were it not for the provision of the justifying screw equipments 80 illustrated in Figures 2 and 5 of the drawings. After each adjustment of the eccentric sleeve 76 the screw adjustments 80 are utilized to adjust the gears 79 and 73 relative to the shaft 75, thereby to restore perfect registering relation of the male and female die elements.

10 The marking equipment as herein described is capable of being operated at great speed in marking and has a capacity for making heavy impressions with rotary die elements which may cover the whole can end with embossing instead of the usual one or two lines of characters. It will also be obvious that the marking equipment and the end closure feeding devices can be adjusted upwardly or downwardly as a whole in order to adapt the closing machine for closing containers of different heights. It is also possible to utilize the adjusting equipments 51, 59 for adjusting the marker parts and the end closure feeding parts relatively to accurately adjust the cooperative relation of these parts.

15 It is of course to be understood that the details of structure and arrangement of parts may be variously changed and modified without departing from the spirit and scope of the invention.

20 I claim:

1. In can end closure marking means, a pair of rotary shafts disposed in parallel spaced relation and connected by intermeshing gears of like diameter mounted thereon, means providing a bearing for each shaft, said last named means including a bearing bore and an eccentric sleeve surrounding one said shaft as a bearing sleeve and having rotary bearing contact in said bearing bore and being adjustable about said one shaft for altering the spaced relation of the shafts, a worm gear portion on said sleeve intermediate of the ends thereof, a captive screw engaging said worm gear portion for imparting movements of adjustment to said sleeve, and marking elements carried by the shafts and opposed for engaging in rolling contact with end closures passed between said elements.

2. In can end closure marking means, a pair of rotary shafts disposed in parallel spaced relation and connected by intermeshing gears of like diameter mounted thereon, means providing a bearing for each shaft, said last named means including an eccentric sleeve surrounding one said shaft as a bearing sleeve and having rotary bearing contact in said bearing means and being adjustable about said one shaft for altering the spaced relation of the shafts, means for imparting movement of adjustment to said sleeve, male and female marking die elements carried by the shafts and opposed for engaging in rolling contact with end closures passed between said elements, the gear on the eccentric sleeve surrounded shaft being mounted for movement of adjustment about the axis of and relative to said sleeve surrounded shaft, and justifying means for adjusting the adjustably mounted gear on the eccentric sleeve surrounded shaft relative to said sleeve surrounded shaft following adjustments of the sleeve for restoring the desired accurate alignment of said male and female die elements.

3. In can end closure marking means, a pair of rotary shafts disposed in parallel spaced relation, means providing a bearing for each shaft, said last named means including an eccentric

sleeve surrounding one said shaft as a bearing sleeve and having rotary bearing contact in said bearing means and being adjustable about said one shaft for altering the spaced relation of the shafts, means for imparting movement of adjustment to said sleeve, an adjuster sleeve fixed to the eccentric sleeve surrounded shaft and having a lug extension with a longitudinal recess therein, a gear loosely mounted on said adjuster sleeve and having a pin projecting therefrom into said recess, a gear of like size secured to the other shaft and meshing with the first mentioned gear, male and female marking die elements carried by the shafts and opposed for engaging in rolling contact with end closures passed between them, and adjuster screws carried by said lug and engageable at opposite sides of said pin for adjusting the relation of the gear and the sleeve surrounded shaft, thereby to restore the desired accurate alignment of said male and female marking elements following adjustments of the eccentric sleeve.

4. In can end closure marking means, a pair of rotary shafts disposed in parallel spaced relation and connected by intermeshing gears of like diameter mounted thereon, means providing bearing for each shaft, said last named means including an eccentric sleeve surrounding one said shaft as a bearing sleeve and having rotary bearing contact in said bearing means and being adjustable about said one shaft for altering the spaced relation of the shafts, means for imparting movement of adjustment to said sleeve, male and female marking die elements carried by the shafts and opposed for engaging in rolling contact with end closures passed between said elements, and means for imparting movement about its axis to one shaft relative to the other shaft to restore perfect registry of the marking die elements after an adjustment of the eccentric sleeve has been effected.

5. In can end closure marking means, a pair of rotary shafts disposed in parallel spaced relation and connected by intermeshing gears of like diameter mounted thereon, means providing bearing for each shaft, said last named means including an eccentric sleeve surrounding one said shaft as a bearing sleeve and having rotary bearing contact in said bearing means and being adjustable about said one shaft for altering the spaced relation of the shafts, means for imparting movement of adjustment to said sleeve, male and female marking die elements carried by the shafts and opposed for engaging in rolling contact with end closures passed between said elements, one said gear loosely surrounding the shaft on which it is mounted, and means causing said loosely mounted gear and the shaft it surrounds to move in unison, said last named means being adjustable to impart relative movement between the loosely mounted gear and the shaft it surrounds for justifying the registry of the marking die elements following adjustments of the eccentric sleeve.

6. In can end closure marking means, a pair of rotary shafts disposed in parallel spaced relation and connected by intermeshing gears of like diameter mounted thereon, means providing bearing for each shaft, said last named means including an eccentric sleeve surrounding one said shaft as a bearing sleeve and having rotary bearing contact in said bearing means and being adjustable about said one shaft for altering

the spaced relation of the shafts, means for imparting movement of adjustment to said sleeve, male and female marking die elements carried by the shafts and opposed for engaging in rolling contact with end closures passed between said element, one said gear loosely surrounding the shaft on which it is mounted, and means causing said loosely mounted gear and the shaft it surrounds to move in unison, said last named means comprising a sleeve fixed to the loose gear surrounded shaft and having a radially projected lug equipped with an elongated slot, said loose gear having a projection extending into said slot, and adjuster screw means for adjustably fixing the position of said gear projection in said slot thereby to restore the desired accurate alignment of said male and female marking elements following adjustments of the eccentric sleeve.

20 7. In can end closure marking means, a pair of rotary shafts disposed in parallel spaced relation and connected by intermeshing gears of like diameter mounted thereon, means providing bearing for each shaft, said last named means including an eccentric sleeve surrounding one said shaft as a bearing sleeve and having rotary bearing contact in said bearing means and being adjustable about said one shaft for altering the spaced relation of the shafts, means for imparting movement of adjustment to said sleeve, male and female marking die elements carried by the shafts and opposed for engaging in rolling contact with end closures passed between said elements, one said gear loosely surrounding the shaft on which it and the eccentric sleeve are mounted, and means causing said loosely mounted gear and the shaft it surrounds to move in unison, said last named means comprising a sleeve fixed to the loose gear surrounded shaft and having a radially projected lug equipped with an elongated slot, said loose gear having a projection extending into said slot, and adjuster screw means for adjustably fixing the position of said gear projection in said slot, thereby to restore the desired accurate alignment of said male and female marking elements following adjustments of the eccentric sleeve.

45 8. In can end closure marking means, a pair of rotary shafts disposed in parallel spaced relation and connected by intermeshing gears of like diameter mounted thereon, means providing a bearing for each shaft, said last named means including an eccentric sleeve surrounding one said shaft as a bearing sleeve and having rotary bearing contact in said bearing means and being adjustable about said one shaft for altering the spaced relation of the shafts, means for imparting movement of adjustment to said sleeve, male and female marking die elements carried by the shafts and opposed for engaging in rolling contact with end closures passed between said elements, said adjustment movement imparting means including a worm gear portion on said sleeve intermediately of the ends thereof, a captive screw engaging said worm gear portion for imparting movements of adjustment to said sleeve, and justifying means for adjusting the gear on the eccentric sleeve surrounded shaft relative to said surrounded shaft following adjustments of the sleeve for restoring the desired accurate alignment of said male and female die elements.

ALFRED L. KRONQUEST.
